UNITED STATES PATENT OFFICE

2,542,977

MATERIAL LOADING APPARATUS

Charles F. Ball, Franklin, Pa., assignor to Joy
Manufacturing Company, a corporation of
Pennsylvania

Application March 7, 1947, Serial No. 733,007

12 Claims. (Cl. 198—10)

1 This invention relates to material loading apparatus and more particularly to improvements in the material gathering mechanism of an apparatus for loading coal, iron ore, hard rock or similar materials in mines.

In material loading apparatus, particularly in mobile loading machines for loading coal, iron ore, hard rock or similar materials in mines, the loose material to be loaded is moved onto the loading conveyor by means of swingable gathering arms driven by crank disks which run close to the top deck of the gathering head. A very desirable gathering arrangement for material loading apparatus includes an inclined deck up which material may be moved for deposit on a conveyor, and gathering arm mechanisms including gathering arms guided at their upper ends and moved by crank pins carried by disks rotating on axes perpendicular to the plane of the deck surface. With such an arrangement, abrasive material being handled by the loading apparatus tends to work in and pack between the disk and the underlying deck surface, exerting considerable drag with a resultant large loss of power and overloading of the material gathering mechanisms. Desirably, in order that the deck surface may have a minimum number of projections above it, the crank disks may be recessed into the deck surface and rotate, as it were, in shallow pockets. This does not, however, obviate the difficulty from dirt and other abrasive material working its way between the bottom surfaces of the crank disks and the underlying deck surface. It is further desirable that the crank disks be supported and driven by heavy shaft members received in a drive mechanism carried by the deck-wall which underlies the crank disks, and this results in the formation of an opening through the underlying wall near the central portion of the latter, through which opening it is important to prevent the passage of dirt and other abrasive material into the bearing structure. Accordingly, it is desirable, for the reasons pointed out, to use a crank disk received in a pocket formed in the deck surface, with, in order to provide as much strength as possible, the lower surface of the crank disk very close to the wall which forms the bottom wall of the pocket, and to provide adequate means not only for preventing the ingress of dirt or other abrasive material into the bearings for the crank disk but also adequate means for preventing the building up or packing of a solid layer of abrasive material between the bottom of the disk and the opposed surface, and it is the contemplation of the present invention to provide an improved structure including means for accomplishing each and both of these results. As this crank disk and shaft drive of the gathering arms possess many advantages, it is very important to avoid the build-

2 ing up or packing of a solid layer of abrasive material between the disk and the underlying deck plate, for a substantial portion of the power required to effect disk rotation may, under such conditions, be due to friction, and were nothing done to keep down this friction, the gathering mechanism would be overloaded, greatly decreasing operating efficiency.

It is accordingly an object of the present invention to provide a material loading apparatus having improved material gathering mechanism which overcomes, to a large extent, the packing of dirt or other abrasive materials between the close running surfaces of moving parts of the gathering mechanism, and for preventing access of dirt to the bearing structure. Another object is to provide an improved material gathering mechanism of the kind wherein crank disks are employed for actuating gathering arms, having improved means substantially to avoid packing of dirt between the bottoms of the disks and the closely underlying surfaces of the deck of the gathering head. A further object is to provide an improved gathering mechanism wherein the rotatable crank disks for actuating the gathering arms are formed with bottom cavities for receiving any dirt obtaining access between the disks and the closely underlying surfaces of the head plate, and to provide discharge openings or dirt vents in the underlying plate with which the cavities communicate as the disks revolve for discharging any dirt collected in the disk-cavities. Still another object is to provide a gathering head having crank disks for driving the gathering arms, wherein the head deck is recessed in a novel manner to receive the crank disks, with the deck surface closely underlying the disks, and having improved means for preventing the packing of dirt or other abrasive material between the disks and the underlying deck surface. A still further object is to provide the deck recesses with open sides, with the crank disks projecting laterally beyond the sides of the deck, so that the dirt-collecting cavities in the disk-bottom at such projecting sides open freely downwardly in an improved manner, thereby to supplement, to some extent, the bottom discharge openings in the underlying deck surface. Yet another object is to provide improved dirt relief means for the crank disk bearings, so that access of dirt to and packing of dirt around the upper disk bearing is substantially precluded. These and other objects and advantages of the invention will, however, hereinafter more fully appear.

In the accompanying drawings there is shown for purposes of illustration one form which the invention may assume in practice.

In these drawings:

60 Fig. 1 is a top plan view of a gathering head

of a loading machine in which an illustrative form of the invention is embodied.

Fig. 2 is a fragmentary view of the gathering head shown in Fig. 1, with parts of the outer casing broken away to show structural details.

Fig. 3 is an enlarged detail vertical sectional view taken on line 3—3 of Fig. 1.

Fig. 4 is an enlarged vertical sectional view taken substantially on line 4—4 of Fig. 1, but with the crank pin turned through 90° into its forward position, showing details of the crank disk and arm structure.

Fig. 5 is a horizontal sectional view, on a reduced scale, taken on line 5—5 of Fig. 4.

Fig. 6 is a plan view of the portion of the head-deck underlying the crank disk and with the latter removed, showing the dirt discharge opening.

In this illustrative embodiment of the invention, there is shown a gathering head, generally designated 1, of a mobile loading machine of the frontal attack type for loading coal, iron ore, hard rock or similar material from the floor of a mine. The gathering head is normally disposed in a downwardly inclined position, as shown in Fig. 2, during the loading operation and has an inclined top deck 2 and a forward penetrating nose 3 provided with a series of toothlike projections or serrations 4 across its front penetrating edge. Arranged centrally and longitudinally of the gathering head is a conventional endless loading conveyor 5 for moving material rearwardly of the head, while arranged at the opposite ends of the front receiving end of the conveyor are flat circular plates or disks 6 of identical construction having their smooth upper plane surfaces 7 lying substantially flush with the top surface of the deck. As illustrated, the deck has its top plate circularly cut away at 8 at the front and rear of each disk and the deck is circularly recessed at 9, to countersink the disk within the deck, and the recess 9 open laterally at their opposite sides and the outer sides of the disks overhang the outer sides of the gathering head while the inner sides of the disks run close to the loading conveyor 5. These disks have integral crank arm portions 10, 10 formed with upstanding crank pins 11, 11, herein located 180° apart with respect to the disk axes and to which swingable gathering arms 12 are pivotally connected. These gathering arms have forwardly projecting picks or claws 13, 13 lying above the head nose 3 close to the top deck surface and are armed with picks or teeth 14. The gathering arms have curved guide bar portions 15, 15, likewise armed with picks or teeth, projecting rearwardly from the arm pivots and formed with downwardly opening arcuate slots 16, which receive guide blocks 17 pivotally mounted on the gathering head. These curved guide bars and guide blocks serve to compel movement of the gathering arms in predetermined paths as the crank disks are rotated so that the gathering arms gather the material and move the material rearwardly along the top of the head-nose and deck toward the receiving end of the loading conveyor 5. It will be noted that the gathering arms and their guide bar portions are relatively close to the top of the head deck and the plane top surfaces of the crank disks so that an effective wiping or clearing action is attained, preventing the jamming and crushing of hard lumps of material being loaded, greatly increasing operating efficiency. Also, by providing the gathering head with a smooth top deck and by avoiding pockets or recesses in the disks and

undue projections on the arms and other associated parts, undesirable pocketing and trapping of hard lumps is substantially avoided.

As shown in Fig. 4, the crank pins 11 support bearings 19 enclosed within the hublike portions 20 of the gathering arms, and a retainer ring 21 is supported on the crank pin and fitted within the bottom bore of the arm hub; and this retainer ring is formed with a peripheral upstanding flange fitted in a circular recess in the arm hub, thereby to provide a dirt seal. A washer 22, secured to the upper end of the crank pin, engages the inner race of the upper bearing for holding the bearings and arm hub in place on the crank pin. Each crank disk has a downwardly extending axial shaft 25 fitted and secured in the hub 26 of a worm wheel 27. The worm wheel hub is journaled in spaced upper and lower bearings 28 supported within a gear casing 29 attached at its upper side to a plate 30 integral with the gathering head beneath the head deck. The upper, principal bearing is arranged with respect to its support and the disk so that the maximum radial thrust of the disk on the bearing is supported close to the point of bearing support. A worm 31 meshes with and drives the worm wheel and is secured to a transverse shaft 32, likewise suitably journaled within the gear casing. Each worm shaft has a sprocket 33 secured thereto exteriorly of the gear casing, and each sprocket is driven by a drive chain 34 in any suitable and known manner. By supporting the gear casing only at its upper side on the gathering head, a much stronger structure results. Such manner of support of the gear casing necessitates, however, the top plate 30 closely to underlie the crank disk, and such close relation of the disk and plate is desirable so that stable support of the disk with respect to its bearing mounting is provided. An annular member 35 is secured to the upper side of each gear casing close to the bottom of the crank disk and has an upstanding annular flange 36 received in an annular recess formed between depending annular flanges 37 on the bottom of the crank disk, thereby to provide a dirt seal. Since the manner of mounting the crank disks and the driving means therefor are fully disclosed in a copending application to W. E. Overturf, Serial No. 732,958, filed March 7, 1947, further description thereof herein is deemed unnecessary.

As clearly shown in Fig. 4, the top plane surface 38 of the deck plate 30 closely underlies the bottom surface 39 of the crank disk, and the plate is formed with a bore 40 within which the outer annular flange 37 of the crank disks projects, and the outer peripheral surface of the outer flange 37 runs close to the walls of the bore, as shown. The improved means for preventing the packing of dirt or other material between the close running surfaces of the disks and head plate comprises cavities provided by hollowing out, at 42, the bottom of each disk all around except beneath the crank arm portion 10, and the cavity so provided is adapted to receive the dirt or other material which passes beneath the disk. The closely underlying surface of the head plate 30 is cut away at 43 to provide a dirt vent, and this cut-away portion cuts through the walls of the bore 40 at 44. Thus, as the crank disk revolves, the disk cavity passes over the opening 43 in the head plate so that any dirt collected in the disk cavity may be thrown out and may drop down through the open bottom of the head. Also,

any dirt collected between the walls of the bore 40 and the outer disk-flange 37 will be discharged through the cut-away portion 44 and the opening 43. The provision of the relief cavity in the bottom of each crank disk, even while the disk bottom runs close to the top surface of the underlying plate, prevents packing of dirt, since the dirt is loosely received in the disk-cavity, and so is readily carried around, as the disk revolves, and discharged through the dirt vent. The cavities 42 in the disk-bottom, at the outer overhanging sides of the disk, freely open downwardly so that dirt may drop downwardly in such manner as to supplement, to some extent, the bottom discharge openings 43. Thus supplemental dirt vents are provided at the outer sides of the head, and these vents and the discharge vents 43 are cumulatively of a radial dimension equal to the radial dimensions of the cavities in the disk-bottoms, so that any dirt which may collect in the cavities is effectively discharged.

As a result of this invention, an improved material loading apparatus is provided having improved gathering mechanism wherein excessive friction, due to packing of dirt or other abrasive material between the close running parts and access of dirt to the bearing structure, are substantially avoided. It will further be evident that by recessing the crank disks into the deck of the gathering head, with the top surfaces of the crank disks flush with the top surface of the deck, and by running the gathering arms and the curved guide bars relatively close to the tops of the disks and head-deck, an effective clearing action is attained. It will also be evident that by the provision of the cavities in the bottoms of the crank disks and the cut-away portions in the closely underlying plates of the head-deck, packing of dirt or other material between the close running surfaces of the disks and head plate is substantially avoided. Further, by providing crank disks with bottom dirt-collecting cavities and by arranging the disks so that they overhang at their outer sides the sides of the gathering head, together with the bottom discharge opening in the head-deck, any dirt which collects in the disk cavities may freely drop out. By arranging the deck plate close to the bottoms of the crank disks, a more stable bearing support for the disks results, although such a structure necessitates the close positioning of the head plate to the disk bottoms. The relatively narrow spaces between the disk bottoms and the underlying deck plate do not, however, become packed with dirt since the provision of the bottom disk-cavities and the dirt vents eliminate such packing. Other advantages of the invention will be clearly apparent to those skilled in the art.

While there is in this application specifically described one form which the invention may assume in practice, it will be understood that this form of the same is shown for purposes of illustration and that the invention may be modified and embodied in various other forms without departing from its spirit or the scope of the appended claims.

What I claim as new and desire to secure by Letters Patent is:

1. In a material loading apparatus, a gathering head having a top deck, material gathering mechanism mounted on said head including a rotatable crank disk journaled in said head with its top surface substantially flush with the top surface of said deck, said head having a portion underlying said disk provided with a plane upper

surface lying close to the bottom of said disk, and means for preventing the packing of dirt between the close running surfaces of said disk and head portion comprising a dirt collecting chamber formed in the bottom of said disk and opening downwardly, and an opening in said head portion through which any dirt collected in said disk chamber is discharged as said disk revolves.

2. In a material loading apparatus, a loading head having a top deck, material gathering mechanism mounted on said head including a rotatable crank disk journaled in said head with its top surface substantially flush with the top surface of said deck, said disk having a solid crank arm portion and an upstanding crank pin at the outer extremity of said crank arm portion, said head having a portion underlying said disk provided with an upper plane surface lying close to the bottom of said disk, and means for preventing the packing of dirt between the adjacent surfaces of said disk and said head portion comprising a hollowed out portion all around the bottom of said disk except along the crank arm portion to provide a dirt collecting cavity, and said head portion having a discharge opening therethrough with which the cavity provided by said hollowed-out portion communicates as said disk revolves.

3. In a material loading apparatus, a loading head, material gathering mechanism mounted on said head including a rotatable crank disk for actuating a gathering arm, a bearing support on said head beneath said disk by means of which the latter is journaled, said head having a portion below said disk provided with a plane top surface lying close to the bottom of said disk, said head portion having a circular bore receiving a portion of said bearing support, and means for preventing the packing of dirt between the close running surfaces of said disk and said head portion comprising a dirt collecting chamber formed in the bottom of said disk and facing downwardly, and an opening in said head portion cutting through the walls of said bore for discharging any dirt collected in said disk-chamber and between the walls of said bore and said bearing support portion.

4. In a material loading apparatus, a gathering mechanism including a rotatable crank disk having an upstanding crank pin for actuating a gathering arm, a bottom support by means of which said disk is journaled and including a plate underlying said disk with its plane top surface lying close to the bottom surface of said disk, and means for preventing the packing of dirt between the close running surfaces of said disk and plate comprising a dirt receiving cavity in the bottom of said disk and a discharge opening in said plate with which said cavity communicates as said disk revolves.

5. In a material loading apparatus, a gathering mechanism including a rotatable crank disk having an upstanding crank pin for actuating a gathering arm, a bottom support by means of which said disk is journaled and including a plate underlying said disk with its top surface lying close to the bottom surface of said disk, said disk having an annular hub-like portion projecting from its bottom and said plate having a circular bore with which the outer peripheral surface of said annular portion has a close running fit, and means for preventing the packing of dirt between the close running surfaces of said disk and plate comprising a dirt receiving cavity in the bottom of said disk and a discharge

opening in said plate with which said cavity communicates as said disk revolves, said plate-opening cutting through the walls of said bore to discharge any dirt between the walls of said bore and said annular disk portion.

6. In a material loading apparatus, a gathering mechanism including a rotatable crank disk having an upstanding crank pin for actuating a gathering arm, said disk having a solid crank arm portion at the outer extremity of which said crank pin is carried, a supporting plate underlying said disk with its plane top surface lying close to the bottom surface of said disk, and means for preventing the packing of dirt between the close running surfaces of said disk and plate comprising a dirt receiving cavity all-around the bottom of said disk except along said crank arm portion and a discharge opening in said plate with which said cavity communicates as said disk revolves.

7. In a material loading apparatus, a gathering head, material gathering mechanism mounted on said head including a rotatable crank disk for actuating a gathering arm, a bearing mounting supported by said head beneath said disk and supporting a bearing by means of which said disk is rotatably supported and closely underlying said disk so that stable support of said disk with respect to its bearing mounting is provided, said head having its top surface closely adjacent to the bottom of said disk, and dirt relief means associated with said disk and said head for preventing the packing of dirt between the close running surfaces of said disk and head and for preventing access of dirt to the bearing, said dirt relief means including a dirt receiving cavity in the bottom of said disk and a dirt vent in said head, said cavity and said vent being so arranged that as said disk revolves any dirt collected in said cavity may drop down through said vent.

8. In a material loading apparatus, a gathering head having a top deck, material gathering mechanism mounted on said head including a rotatable crank disk, said deck having a portion underlying said disk provided with a plane upper surface close to which the bottom of said disk moves during disk rotation, and means for preventing the packing of dirt between said surfaces comprising a dirt receiving chamber formed in the bottom of the disk and opening downwardly and an opening provided by said deck portion through which dirt which obtains access to said disk chamber is discharged as the disk revolves.

9. In a material loading apparatus, a gathering head having a top deck, material gathering mechanism mounted on said head including a rotatable crank disk, said deck having a portion underlying said disk provided with a plane upper surface close to which the bottom of said disk is disposed, said deck having an opening therethrough and supporting a bearing for said disk coaxial with said opening, and said disk having a driving and supporting member extending through said opening, and means for preventing the packing of dirt between the lower surface of said disk and the upper surface of said deck portion and for preventing the access of dirt to said bearing comprising an arcuate dirt collecting chamber disposed outwardly of said opening and inwardly of the periphery of said disk, and dirt discharge means in said deck portion through which dirt collected in said arcuate chamber may be discharged as said disk revolves.

10. In a material loading apparatus, a gathering head having a top deck, material gathering mechanism mounted on said head including a rotatable crank pin supporting crank disk, said deck having a portion underlying said disk provided with a plane upper surface close to which the bottom of said disk is disposed, said deck having an opening therethrough and supporting a bearing for said disk coaxial with said opening, and said disk having a driving and supporting member extending through said opening, and means for preventing the packing of dirt between the lower surface of said disk and the upper surface of said deck portion and for preventing the access of dirt to said bearing comprising an arcuate dirt collecting chamber disposed outwardly of said opening and inwardly of the periphery of said disk, and dirt discharge means in said deck portion through which dirt collected in said arcuate chamber may be discharged as said disk revolves, said disk having a central portion lying in part within said opening and a connected radially extending crank arm forming portion intermediate the ends of said arcuate chamber supporting and providing a reinforcing member for said crank pin.

11. In a material loading apparatus, a gathering head having a top deck formed with a recess open at the outer side of the head, material gathering mechanism including a rotatable crank disk journaled within said head and arranged within said recess with the bottom of said disk lying close to the bottom of said recess, said disk at its outer side projecting outwardly through the open side of said recess so that the disk overhangs the side of said head, and means for preventing the packing of dirt between said disk and the recess bottom comprising a cavity in the bottom of said disk having a portion which extends outwardly beyond the outer side of the bottom of the recess, and dirt discharge means in the recess-bottom and spaced inwardly of the disk periphery and with which said cavity communicates as said disk revolves, said outwardly extending portion of said cavity which opens freely downwardly at the outer side of said head supplementing said discharge means in the discharge of dirt from said cavity.

12. In a material loading apparatus, a gathering head having a top deck formed with a recess opening at the outer side of the head, material gathering mechanism including a rotatable crank disk journaled within the head and arranged within the recess with the bottom of the disk lying close to the bottom of the recess, and means for preventing the packing of dirt between said disk and the recess bottom comprising a cavity in the bottom of the disk of substantial radial dimension, and discharge vents from said recess cumulatively of a radial dimension equal to the radial dimension of the cavity and with which said cavity communicates as the disk revolves.
